COIN-CONTROLLED LOCK MECHANISM.

1,393,201.

Specification of Letters Patent. Patented Oct. 11, 1921.

Application filed July 17, 1920. Serial No. 397,120.

To all whom it may concern:

Be it known that I, RALEIGH B. BUZZAIRD, a citizen of the United States, and a resident of Washington, in the District of Columbia, have invented a new and useful Improvement in Coin-Controlled Lock Mechanism, of which the following is a specification:

This invention is an improvement in coin-locking means for parcel-checking lockers.

10 The doors of such lockers are locked by the users through the deposit of a coin, which also enables the owner of the checked property to remove the key from the lock, to constitute his check. By use of the key he can 15 unlock the locker again and take out his belongings, the key then being locked in the lock against theft or loss.

The object of the invention is to prevent 20 patrons losing their service by operating the lock after deposit of a coin while the door is standing open. In such event, of course, the bolt would be projected, but the door would not be locked, and as the coin would have passed beyond its operative position, 25 the patron would be obliged to retract the bolt, put in another coin and operate the lock again. In an application filed of even date herewith I disclose and claim a construction in which a lip on the door closes the entrance 30 to the coin-drop when the door is closed, so that in consequence the coins must be fed to the lock when the door is open, which makes it possible for thoughtless persons to project the bolt when the keeper on the door is not 35 present to receive it. In that application I also disclose and claim a coin-arrester, which normally obstructs the path of the coin to the coin-mechanism of the lock and which renders any attempt to operate the lock idle, 40 until the door is closed, at which time the lip acts upon the arrester to remove it from the coin. It is also incidentally shown in that case that the auxiliary part of the lock which constitutes the arrester has a portion which 45 normally blocks or restrains operation of the lock mechanism proper, more especially by coöoperating with a detent which holds the bolt against movement from unlocking to locking position and which is displaced 50 through the instrumentality of the coin.

The present invention comprises, specifically, such means for blocking the operation of the lock mechanism, and in its broad aspect is generic to auxiliary means for pre-

venting operation of the coin lock after deposit of the coin and while the door subject to the lock is open. Claims are also included herein to the combination of both forms of means, serving as a double-check to prevent patrons losing their coins, and also to combinations including door-operated means for closing the coin-entrance. 55

In the accompanying drawings, forming part hereof:

Figure 1 is a front elevation of a locker 65 and lock, showing how the door-lip closes the coin-entrance and coöperates with the auxiliary means of the lock;

Fig. 2 is a front elevation of the lock on a larger scale; 70

Fig. 3 is a rear elevation of the lock in the unlocked condition, with the cover of the coin-disk casing partly broken away, showing a coin in the coin disk bearing against the detent, movement of which is prevented 75 by the auxiliary device; and

Figs. 4 and 5 are horizontal sections on the line 4—4 of Fig. 2, showing the auxiliary member in normal position, and repressed by the door-lip, respectively. 80

The general lock construction in which the instant invention is shown embodied is the invention of another, and is illustrative of the combination, the invention being applicable, however, to other forms and types 85 of coin-controlled locker locks.

The front plate or escutcheon 1 has a knob 2, a coin-entrance 3 and the key-slot end of a key-cylinder 4 on its outer side. This key-cylinder and its cylinder-casing 5 constitute 90 a well-known form of lock unit, containing tumbler arrangements whereby the key can be removed in the locking condition only, and is locked in the lock by the tumblers when the lock is open. These matters being 95 familiar require no illustration.

A swinging bolt 8 is pivoted at 11, and is projected by a spring 17. The bit 14 of the key-cylinder coöperates with a recess or socket 15 in the rear portion of the bolt. A 100 bell-crank detent 18 is pivoted at 19 and its rearwardly extending arm is formed with a primary holding shoulder 21, which coöperates with a projection 23 on the bolt to hold the latter in its fully retracted condition, the 105 detent having a spring 24 whereby it engages automatically.

The contact extremity of the downwardly

extending arm 26 of the detent is arranged to be encountered by a coin *a* carried by a rotary coin-disk 30 having an eccentric coin-pocket 31. The disk is connected to the knob 2 on the outside, and receives the coin from a coin-drop 29 on the inside leading from the coin-entrance 3.

When the detent is displaced through the deposit of a coin and the turning of the knob, the bolt is freed to move to its locking or projected position. The key-cylinder being connected with the bolt is also moved to the position in which the key can be removed by the user, to constitute his check. When he wishes to regain his property he inserts the key and turns it in the unlocking direction, thereby retracting the bolt, which is caught and held by the detent, the key being thereby locked in the cylinder until the next checking operation.

As in my other application aforesaid, a lip 46 is fixed to the free edge of the door 47, of such proportions and arrangement as to cover completely and closely the coin-entrance 3 in the front plate 1 of the lock, and overlap adjoining portions of the plate. With this lip in closed position, it is impossible to introduce a coin or any other object into the coin passage and thence into the interior of the lock. Thus, an inattentive person cannot lose a coin in the lock of a locker which is in use; nor can the service of the locker be obtained without cost by placing articles in it, closing the door and then displacing the detent 18 by a wire inserted through the coin-drop.

The auxiliary means of this invention, as embodied in the particular construction illustrated, comprises a member 48 in the interior of the lock, which possesses a portion 54 adapted to engage or block the detent 18, so as to prevent premature operation thereof to release the bolt 8. This member is actuated through an opening 52 in the front plate by the lip 46, preferably through the intermediary of a finger 51 on the member 48 projecting outward through the opening, in position to be struck and repressed by the lip when the door is closed.

The form and arrangement of the member or part 48 and its specific mode of coöperation with the coin-lock mechanism may be varied. Preferably it is in the form of a substantially horizontal piece in the lock, transverse to the coin-drop and the depending arm 26 of the detent, which are substantially parallel and opposite each other, and acting upon both. One end of the member may be pivoted upon a lug 50 bent out of the inner wall of the coin-drop. The other end is hooked, shouldered or provided with a projection or recess, to form the portion 54, which is normally disposed in front of the arm of the detent to prevent the same moving sufficiently under the

action of the knob and coin to release the bolt. An intermediate portion 49 is formed as a shoulder or projection which normally intercepts the path of the coin sufficiently to prevent it from reaching the coin-disk. A spring 53 normally holds the member 48 in its detent-blocking and coin-arresting position, and returns it automatically to such position after being displaced by the action of the door-lip.

It will, therefore, be understood that after a coin has been put in the lock, with the door open, and even if the coin could reach the coin-disk, it will be impossible to project the bolt by turning the knob, because the detent is positively held. The coin-arrester, when present, however, prevents the coin entering the pocket of the disk.

Various other embodiments and applications of the invention will suggest themselves to those skilled in the art. I do not necessarily limit myself to the detent 18 as the part of the coin-lock mechanism proper with which the blocking device coöperates.

What I claim as new is:

1. The combination of a coin-controlled lock lockable only upon deposit of a coin and having manually operated means to produce the locking, a door to be locked, and auxiliary means to prevent locking of the lock while the door is open.

2. The combination of a stationary coin-controlled lock lockable only upon deposit of a coin, and having manually operated means to produce the locking, said lock having a front plate with an opening, auxiliary means in the lock to prevent locking thereof, a door to be locked, and a lip on the door which in closing acts upon said auxiliary means through said opening to permit the locking of the lock.

3. The combination of a coin-controlled lock, having manually operated means to produce the locking, auxiliary means in the lock for preventing locking thereof, a door to be locked, and means whereby closing of the door displaces said auxiliary means.

4. The combination with a lock having a bolt, coin means controlling the protraction of the bolt, and means which must be operated manually to cause protraction, of an auxiliary member blocking the lock mechanism against locking action and adapted to be displaced by the closing of a door subject to the lock bolt.

5. In a coin-controlled lock, the combination of a bolt, a detent therefor, coin means for releasing the detent, an auxiliary device for blocking movement of the detent, and means whereby closing of a door subject to the lock displaces said auxiliary device.

6. The combination of a lock having a bolt and coin means controlling the protraction of the bolt, a coin-drop, auxiliary means internally obstructing the coin drop, and

blocking the lock mechanism against locking, and means whereby closing of the door subject to the lock bolt displaces said obstructing and blocking means.

- 5 7. The combination of a stationary lock having a bolt and coin means controlling the protraction of the bolt, a coin drop, auxiliary means internally obstructing the coin drop and blocking the lock mechanism
- 10 against locking, a door subject to said lock bolt, and a lip on the door adapted to displace said obstructing and blocking means.
8. The combination of a stationary coin-controlled lock having a bolt protractible only upon deposit of a coin, a coin-drop, manually-operated means whereby the user causes the locking of the bolt in the presence of a coin, an auxiliary spring-pressed member in the lock having a portion ob-
- 20 structing the coin-drop and a portion blocking the lock mechanism against locking, and means whereby closing of a door subject to said lock displaces said auxiliary member.
- 25 9. The combination of a stationary coin-controlled lock having a bolt protractible only upon deposit of a coin, a coin-drop, means whereby the user causes the locking of the bolt in the presence of a coin, an aux-
- 30 iliary spring-pressed member in the lock arranged to both obstruct the coin-drop and block the lock mechanism against locking and having an outward projection, and a door subject to the lock having a lip to re-
- 35 press said projection.

10. In a coin-controlled lock, the combi-

nation of a bolt, a coin-drop, a coin-mover at the base of the drop, a pivoted detent for the bolt having an arm extending downward alongside the coin-drop to the vicinity of 40 the coin-mover, an auxiliary device co-operating with both the coin-drop and said arm, and means whereby said device is displaced by the closing of a door subject to the lock.

11. The combination of a stationary manually-operated coin-controlled lock having a coin-entrance and lockable only upon deposit of a coin therein, a door having a lip to close said entrance, and auxiliary means to prevent locking of the lock while the door 50 is open.

12. The combination of a stationary manually-operated coin-controlled lock having a coin-entrance and lockable only upon deposit of a coin therein, a door having a 55 lip to close said entrance, an auxiliary member in the lock blocking the lock mechanism against locking, and means whereby said member is displaced by the door-lip in closing.

13. The combination of a stationary manually-operated coin-controlled lock having a coin-entrance and lockable only upon deposit of a coin therein, a door having a lip to close said entrance, and auxiliary means in 65 the lock having portions normally obstructing the coin passage to the coin mechanism and blocking the operation of said mechanism, said means being displaceable by the door lip when the latter closes the coin-en- 70 trance.
